[57] **ABSTRACT**

Light-absorbing filters comprise a self-supporting poly-

meric film, such as an oriented polyethylene terephthalate film, containing or coated with a lacquer containing a compound which absorbs light in the wavelength band less than 0.4 μm (i.e. UV light). The filters are particularly useful as UV-absorbing filters for use in flashbulbs for color photography. Suitable light-absorbing compounds are hydroxyphenyl benzotriazoles, e.g. 2(2'-hydroxy-3',5'-di-t-amylphenyl)benzotriazole, and hydroxy-substituted benzophenone, e.g. 2,2'-dihydroxy-4,4'-dimethoxy-benzophenone.
